UNITED STATES PATENT OFFICE.

WALTER A. DEVEY, OF AMERICAN FORK, UTAH.

TONGUE-AND-SLOT LOCK.

1,284,615.

Specification of Letters Patent. Patented Nov. 12, 1918.

Application filed February 10, 1913. Serial No. 747,534.

To all whom it may concern:

Be it known that I, WALTER AVERY DEVEY, a citizen of the United States, and a resident of American Fork, in the county 5 of Utah, State of Utah, have invented certain new and useful Improvements in Tongue-and-Slot Locks, of which the following is a specification.

The object of my invention is to provide 10 a simple, easy and efficient inter-lock, for locking the ends of centrifugal or other circular screens.

Referring to the drawings forming a part 15 thereof—

Figure 1 is a perspective view of the screen.

Fig. 2 is a fragmentary view of one end portion of the strip from which the screen is formed.

Fig. 3 is a fragmentary view of the opposite end portion of the strip from which the screen is formed.

Fig. 4 is a section taken upon the line 4—4 of Fig. 1.

Fig. 5 is a section taken along the line 5—5 of Fig. 1.

The portion of the screen intermediate the slot *c* and the adjacent junction edge of the screen form retaining straps for the tongues

30 A and B. integral with the screen. Through the interlocking engagement of the tongues with the slots *c* and the retaining straps, the screen is joined against lateral separation at the junction edges, but at the same time, 35 joined so as to permit circumferential play or movement of the tongues relative to the strap members.

I claim:

1. A screen of the character described 40 formed from a strip of sheet material having its edge portions overlapping, one edge portion being provided with longitudinally extending slots, and the other end portion being provided with slits forming tongues, 45 certain of said tongues extending along one face of the slotted edge portion of said strip, and the remaining tongues extending along the other face of the slotted edge portion

and then passing through the slots formed therein to the opposite side and extending 50 between said first mentioned tongues.

2. A cylindrical screen of the character described formed from a strip of material having one edge portion provided with slits forming tongues and lips, the opposite edge 55 portion of said strip being provided with slots, the edge portions of said strip being positioned in overlapped relation with said lips extending along the outer face of said cylindrical screen and said tongues extending along the inner face of said screen and being then passed through said slots and extending along the outer face of said screen between said lips.

3. A joint for the purpose described 65 comprising a strip section provided with openings extending longitudinally of its edge, and a second strip section provided with slits leading from its edge to form lips and tongues, the edge portions of said strip sections being positioned in overlapping relation 70 with said lips extending along one side of the second strip section and said tongues extending along the opposite side of the second strip section and being then passed 75 through the openings formed therein and extending between said lips.

4. In a lock-joint of the character described a pair of strip sections positioned in overlapping relation, one of said strip sections being provided with openings and the other of said strip sections being provided with tongues and lips, said lips extending along one face of said first-mentioned strip section and said tongues extending along 85 the opposite face of said first-mentioned strip section and being passed through the openings formed therein and then bent to lie flat upon the first-mentioned strip section between said lips with said lips and tongues 90 extending in the same direction.

WALTER A. DEVEY.
